United States Patent Office

Des. 225,280
Patented Nov. 28, 1972

225,280

FRONT PANEL FOR CAMERA OR SIMILAR ARTICLE

James M. Conner, Westchester, N.Y., assignor to Polaroid
Corporation, Cambridge, Mass.

Filed June 17, 1971, Ser. No. 154,256

Term of patent 14 years

Int. Cl. D16—99

U.S. Cl. D61—1

FIG. 1.

FIG. 2.

FIG. 3.

FIG. 1 is a front perspective view of a front panel for camera or similar article showing my new design;

FIG. 2 is a rear perspective view thereof; and

FIG. 3 is a bottom plan view thereof.

I claim:

The ornamental design for a front panel for camera or similar article, as shown.
